UNITED STATES PATENT OFFICE

1,927,453

RADIOFIGURE

Jeanette Hill, New York, N. Y.

Application May 11, 1932. Serial No. 610,673

5 Claims. (Cl. 46—40)

The invention has for an object to provide a novel radio figure comprising an encasing body simulating a sitting animal having a head including eyes and a snout, and forwardly extended feet, and a compact radio receiving set encased within the body and having provision for convenient connection with a power circuit and being controlled by a switch mounted in and simulating the nose proper of the snout, and volume and station selector controls mounted respectively in the feet.

Another object of the invention is to provide novel eye illuminating lights controlled by the radio set controlling switch.

With these and other objects in view which will more fully appear, the nature of the invention will be more clearly understood by following the description, the appended claims, and the several views illustrated in the accompanying drawings.

In the drawings:—

Figure 1 is a face view illustrating the invention.

Figure 2 is a side elevation of the figure shown in Figure 1.

Figure 3 is an enlarged detail section of the snout illustrating the control switch mounting, the switch button being shown moved to the "on" position in dotted lines.

Figure 4 is a detail face view of the parts shown in Figure 3.

Figures 5 and 6 are detail views corresponding to Figures 3 and 4 and illustrating a modified form of switch.

Figure 7 is a view similar to Figure 3 and illustrating a still further modified form of control switch.

Figure 8 is a detail vertical cross section taken through the plane of the station selecting dial.

Figure 9 is a detail horizontal section taken through the axis of the volume control, and

Figure 10 is a detail view illustrating an illuminated eye.

Like reference numerals designate corresponding parts throughout the several figures of the drawings.

In the practical development of the invention, I employ an animal figure generally designated 5 and in this particular disclosure simulating a bear shown in sitting posture and having the usual head with snout 6 and eyes, and including forwardly extended feet designated 7.

The form of the bear provides an encasement for any acceptable form of compact radio power receiver generally designated 8 and which de-

rives the power necessary for its operation from a plug-in connection 9 as illustrated in Figure 2 of the drawings. The receiver set is of conventional form and includes the usual volume control shaft 10, and knob 11 for convenient manipulation by a user of the device. Through the other foot the usual selector shaft 12 is extended and is equipped with a turning knob 13. See Figures 1, 2 and 9. Wires 14 are reversely wrapped at one end about the shaft 12 and secured thereto as indicated at 15 and said wires extend upwardly and are similarly wound around and secured as at 16 to the dial shaft 17 which is rotatably mounted in bearings 18 and carries the usual station indicating dial designated 19 and 70 visible through a window 20 formed in the front of the figure body. See Figures 1, 2 and 8.

A radio speaker unit generally designated 21 is mounted in the interior of the figure body with the base thereof close to the chest of the figure as indicated in Figures 2 and 8. The speaker unit may be secured as at 22 in the figure body and if desired the covering of the figure body extending over the opening in the base thereof may be protected by a screen as indicated at 23.

The radio receiving set is controlled by a switch mounted in the snout of the bear as indicated in Figure 2. The switch is generally designated 24 and may be of any well known "on" and "off" toggle type and secured in the snout of the animal figure as indicated at 25. The switch button 26 which is engaged by the user of the set for controlling the same is connected as at 27 to the throw lever 28 of the switch and is so positioned as to simulate the nose of the animal figure. The switch 24 is shown in detail in Figures 3 and 4, in each of which the control button is shown in the "off" position in full lines and in the "on" position in dotted lines.

The switch is connected by wires 29 with the plug-in connection 9 and with the radio set power mechanism diagrammatically indicated and generally designated 30 so that whenever the device is suitably connected with a source of electrical energy by means of the plug-in connection 9, the switch 24 may be utilized to render the set operative or inoperative. A dial light 31 may be provided and mounted as indicated in Figure 8 so that, when lighted, it will illuminate the dial 19 through the window 20. The light 31 may be connected as at 32 in the switch control circuit 29 so as to be lighted whenever the control switch 24 is "on" and extinguished whenever that switch is in the "off" position.

In addition to the dial light 31, the eyes 33

of the animal figure may be rendered luminous by providing them with small neon tubes as indicated in Figure 10 of the drawings. The terminals of the neon tubes may be connected by 5 circuit wiring 34 with the switch controlled circuit 29 as indicated in Figure 2 of the drawings, the transformer generally designated 35 being interposed in the connection as is usual in light equipments employing neon tubes. In the practical development of the invention the various 10 wiring circuits 29, 32 and 34 may be laid in suitable protective conduits as illustrated in Figure 8 so as to meet the requirements of fire underwriters.

15 In Figures 5 and 6 of the drawings, I have disclosed a modified form of control switch. In these figures the switch is generally designated 36 and is of the "on" and "off" canopy type and is secured as at 37 in the snout of the animal figure. The control button 38 is utilized to turn the control stem 39 of the switch through 180° in snapping the switch on and off and is shaped at its inner face as indicated in Figure 5 so as to lie close to the snout. In Figures 5 and 20 25 6, the control button 38 is shown in full lines in the "off" position and is shown in dotted lines turned 180° to the "on" position.

20 In Figure 7 of the drawings, I have illustrated 30 a still further modification of the control switch in which the toggle stem projecting through the snout of the figure is provided with a ball 40 by which it may be manipulated to control operations of the receiving set.

35 In the foregoing description I have disclosed 40 a novel receiving set mounted in an animal figure which is particularly attractive to both children and grown ups and by reason of the novel arrangement of the receiving set, the controls thereof in the feet of the figure, the station indicating dial and the loud speaker unit in the front wall of the figure, together with the dial and eye lights, offers the advantages of an ornamental animal figure and also a practical and 45 efficient means for obtaining musical entertainment.

50 It is of course to be understood that the details of structure and arrangements of parts may be variously changed and modified without departing from the spirit and scope of my invention.

I claim:—

55 1. As a new article of manufacture, a figure body simulating an animal in sitting posture with forwardly extended feet and a head including a snout, a radio receiving set mounted within the body, control devices for the radio set extending forwardly through the figure body feet to enable manipulation from without the figure body, and a control switch for the radio set 60 mounted in the snout and including a manipulating button simulating the nose of the animal.

2. As a new article of manufacture, a figure

body simulating an animal in sitting posture with forwardly extended feet and a head including a snout, a radio receiving set mounted within the body, control devices for the radio set extending forwardly through the figure body feet to enable manipulation from without the figure body, a station selector dial rotatably mounted in and viewable through the front of the figure body, means to actuate the dial from the control device mounted in one of the feet, and a control switch for the radio set mounted in the snout and including a manipulating button simulating the nose of the animal.

3. As a new article of manufacture, a figure body simulating an animal in sitting posture with forwardly extended feet and a head including a snout, a radio receiving set mounted within the body, control devices for the radio set extending forwardly through the figure body feet to enable manipulation from without the figure body, a station selector dial rotatably mounted in and viewable through the front of the figure body, means to actuate the dial from the control device mounted in one of the feet, a dial light associated with the dial, and a control switch for the radio set mounted in the snout and including a manipulating button simulating the nose of the animal, said button also having connections to control said dial light.

4. As a new article of manufacture, a figure body simulating an animal in sitting posture with forwardly extended feet and a head including a snout and eyes, a radio receiving set mounted within the body, control devices for the radio set extending forwardly through the figure body feet to enable manipulation from without the figure body, lights associated with said eyes, and a control switch for the radio set mounted in the snout and including a manipulating button simulating the nose of the animal, said button also having connections to control said eye associated lights.

5. As a new article of manufacture, a figure body simulating a bear in sitting posture with forwardly extended feet and a head including a snout and eyes, a radio receiving set mounted within the body, control devices for the radio set extending forwardly through the figure body feet to enable manipulation from without the figure body, lights associated with said eyes, a station selector dial rotatably mounted in and viewable through the front of the figure body, means to actuate the dial from the control device mounted in one of the feet, a dial light associated with the dial, and a control switch for the radio set mounted in the snout and including a manipulating button simulating the nose of the animal and operatively connected to switch the radio set, the dial associated light and the eye associated lights simultaneously "on" or "off".

JEANETTE HILL.
